(57) **CLAIM**

The ornamental design for a cup holder adapter, as shown and described.

DESCRIPTION

FIG. 1 is a top plan view of a cup holder adapter showing our new design in the form of a blank; and, FIG. 2 is perspective view of the cup holder adapter of FIG. 1 in its folded configuration.

The solid lines represent cut lines and the dashed lines represent fold lines in FIG. 1. The thickness of the blank is that of a conventional paperboard.
